2 Claims. (Cl. 52—693)

ABSTRACT OF THE DISCLOSURE

A reinforcement for a masonry wall construction having a pair of cylindrical, metal, parallel, spaced side rods and a plurality of cross rods extending between the side rods. The side rods are provided with a plurality of axially aligned spaced grooves opening radially outwardly and having an inner substantially planar rectangular bottom surface extending chordally to the axis of the side rod. The side walls of the grooves are angularly inclined, and the width of the bottom surface is approximately .024 inch with the maximum depth of the grooves being at least approximately .014 inch. The grooves provide effectively positive slip prevention of the rods in the mortar bed of the masonry wall in which they are placed.

This invention relates to masonry reinforcements and in particular to reinforcements for masonry wall constructions.

In one form of masonry wall construction, a plurality of horizontally extending courses of masonry blocks, such as cement blocks, are stacked one upon the other. A bed of mortar is conventionally disposed between each successive course while bonding the blocks to form a unitary wall structure. Such unreinforced block wall constructions, however, are relatively weak as load stresses applied against the wall are not efficiently distributed thereto. To eliminate this disadvantage of such block masonry walls, reinforcements have been placed in the mortar beds between the respective courses. In one type of such reinforcement a pair of spaced side rods are connected by a series of cross rods. An excellent example of such a reinforcement commonly used in the art is that disclosed in Spaight United States Patent No. 2,300,181. Such a reinforcement is commonly called a truss design masonry wall reinforcement. Another form of such reinforcement commonly employed in the art is similar to the above discussed truss design reinforcement but is provided with cross rods extending perpendicularly between the side rods at spaced intervals.

Such reinforced walls have excellent resistance to forces acting against the flat surfaces thereof providing excellent distribution of such forces in both running bond wall constructions (wherein the respective blocks of the successive courses overlap) as well as in stacked bond wall constructions (wherein the respective blocks of the successive courses are vertically aligned). However, with such reinforcements, there is a tendency for the mortar to slip relative to the side rods where forces acting longitudinally of the side rods occur. The present invention is directed to an improved form of reinforcement wherein means are provided for effectively positively precluding such slippage.

Thus, a principal feature of the present invention is the provision of a new and improved reinforcement for masonry wall construction.

2

Another feature of the invention is the provision of such a reinforcement having new and improved means for preventing longitudinal movement of the side rods of the reinforcement relative to the surrounding body of cementitious material such as mortar.

A further feature of the invention is the provision of such a reinforcement wherein the rod movement prevention means comprises a plurality of grooves in the side rods having a new and improved design.

Still another feature of the invention is the provision of such a reinforcement for masonry wall construction having a pair of cylindrical, metal, parallel, spaced side rods and a plurality of cross rods extending between the side rods, means for providing effectively positive retention of the side rods against longitudinal movement through a body of surrounding mortar, the retention means comprising means in the side rods defining a plurality of axially aligned spaced grooves, each groove opening radially outwardly and being defined by a radially inner, substantially planar bottom surface extending parallel to the axis of the side rod and having an axial length of approximately .024", and a pair of opposed, substantially planar side wall surfaces extending angularly outwardly from the axially opposite ends of the bottom surface, the side wall surfaces being oppositely inclined at an angle of approximately 135 degrees to the bottom surface, the depth of the grooves being at least approximately .014".

A yet further feature of the invention is the provision of such a reinforcement wherein the center of the grooves are spaced approximately .125".

Still another feature of the invention is the provision of such a reinforcement wherein the side rods further include an upset portion at the radially outer end of one of the side wall surfaces of the grooves and defining a surface substantially coplanar with that side wall surface.

A yet further feature of the invention is the provision of such a reinforcement wherein the depth of the grooves is made to be a direct function of the diameter of the side rods in which they are provided whereby the spacing between successive grooves is an inverse function of said diameter.

Another feature of the invention is the provision of such a reinforcement wherein the spacing between successive grooves of the plurality is less than .08".

Still another feature of the invention is the provision of such a reinforcement wherein a pair of substantially diametrically opposite pluralities of said grooves is provided in the side rods.

In summary, the invention comprehends an improved grooved side rod structure in a masonry wall reinforcement providing effectively positive slip prevention of the side rods relative to the mortar bed in which they are disposed.

Other features and advantages of the invention will be apparent from the following description taken in connection with the accompanying drawing wherein:

FIGURE 1 is a fragmentary perspective view of a masonry wall construction provided with a reinforcement embodying the invention;

FIGURE 2 is a fragmentary enlarged plan view of the reinforcement;

FIGURE 3 is a fragmentary further enlarged diametric section of the side rod of the reinforcement embedded in a body of mortar in the wall construction;

FIGURE 4 is a fragmentary further enlarged portion of the illustration of FIGURE 3; and

FIGURE 5 is a fragmentary diametric section of a side rod with the dimensional relationships embodying the invention illustrated therein.

In the exemplary embodiment of the invention as disclosed in the drawing, a masonry wall construction generally designated 10 is shown to comprise a plurality of horizontal block courses 11, each formed of a plurality of masonry blocks 12, such as concrete blocks. Between the successive courses 11 a bed of suitable bonding material such as mortar 13 is provided. At the time the mortar is laid on the uppermost surfaces of the top course, a reinforcement 14 is set in the mortar to be embedded therein for reinforcing the joints between the respective blocks. In illustrating the invention, the reinforcement 14 is shown as a truss design type reinforcement, it being understood that other reinforcements, such as the perpendicular cross wire reinforcement discussed above, may be used.

As indicated briefly above, the invention comprehends providing in the reinforcement rod material an improved grooved construction serving to bond the rod against longitudinal movement through the mortar or other cementitious material in which it is embedded. In the truss design reinforcement illustrated in FIGURE 1, the reinforcement is provided with a pair of cylindrical, metal, parallel spaced side rods 15 joined by the diagonal cross wires 16 to form the truss design. Each side rod is provided with means for providing effectively positive retention thereof against longitudinal movement through the mortar, which as illustrated in FIGURE 2 comprises a plurality of axially aligned spaced grooves 17. In the illustrated embodiment four pluralities of such axially aligned spaced grooves are provided, at 90 degree intervals around the circumferential extent of the cylindrical side rod. Each of the pluralities herein is substantially similar and thus the description of the grooves will be limited to the plurality of grooves shown in plan in FIGURE 2, it being understood that each of the three other pluralities may be similar thereto.

As shown in FIGURES 3 and 4, the mortar 13 flows downwardly into the grooves 17 to define a locking portion 18 therein. By preselecting the axial width of the groove at the radially outer surface of the rod 15, a pre-selected high resistance to shear of locking portion 18 from the main body 19 of mortar bed 13 is obtained which effectively positively retains the side rod 15 against longitudinal movement through the mortar bed. Further, by preselecting the flare of the grooves as illustrated in FIGURES 3 and 4, the mortar may be made to flow readily down into the grooves while yet the grooves provide vectorial force components in the direction of the axis of the rod at least approximately equal to the forces acting radially thereon when a force tending to move the rod axially through the mortar bed 13 is applied. Still further, the flare of the grooves is preselected to permit facilitated construction of the reinforcement as by knurling. The invention further comprehends the preselection of the spacing between the grooves to provide the desired effectively positive retention of the rod without excessive groove formation therein. Still further the design of the groove is preselected to permit a maximum axial groove width by forming means such as knurling while precluding flattening of the wire during such forming.

Thus, while grooves have heretofore been employed in such side rods for locking the rods against longitudinal movement, the present invention comprehends an improved groove construction having dimensional characteristics preselected to provide the above discussed features.

More specifically, as shown in FIGURE 5, the side rod 15 is provided with a plurality of grooves 17, each provided with a radially inner, or bottom, substantially planar surface 20 extending parallel to the axis of the side rod. The surface 20 has an axial width a . The radial depth of the groove is designated b . The opposite side wall surfaces 21 and 22 of the groove 17 are substantially planar and extend angularly outwardly from the axially opposite

ends of the bottom surface 20. The angle of the surfaces 21 and 22 herein is substantially similar and is designated c . In forming the grooves 17 as by knurling, an upset portion 23 is provided at the outer end of one side wall surface, such as surface 21, and includes an end surface 24 substantially coplanar with surface 21. The height of the upset portion 23 is designated d . Thus, the radial dimension between the outermost portion of the groove as at the outermost end of the portion 23 and the innermost portion of the groove as at surface 20 is the sum of dimensions b and d designated e .

The axial width of the grooves at the circumference 25 of the side rod 15 is designated f . The center-to-center spacing between successive grooves 17 is designated g . The spacing between successive grooves is designated h .

Side rod 15 herein illustratively comprises a metal wire, which may have any one of a plurality of diameters such as .1875", .1620" and .1483" (respectively nominally termed $\frac{3}{16}$ ", No. 8 and No. 9 wires). The invention comprehends providing the bottom surface 20 with an axial dimension a of a .024" irrespective of the rod diameter. The angle c of the side surfaces 21 and 22 is preferably approximately 135 degrees. The depth of the grooves b is preferably at least .014" and preferably varies as a direct function of the diameter of the rod. Thus, the depth b for No. 9 wire is preferably approximately .014", the depth for No. 8 wire is preferably approximately .016" and the depth for the $\frac{3}{16}$ " wire is preferably approximately .018".

The height d of the upset portion 23 is preferably approximately .003" and, thus, the dimension e for the indicated wires is approximately .017", .019", and .021", respectively.

The width f of the grooves preferably varies directly with the size of the rod. In the illustrated embodiment, the groove width f for the No. 9 wire is preferably approximately .052", for the No. 8 wire is preferably approximately .056", and for the $\frac{3}{16}$ " wire is preferably approximately .060". The spacing g between centers of the respective grooves is preferably constant for each of the different diameter rods and in the illustrated embodiment the dimension g is approximately .125". The spacing h between the successive grooves 17 is preferably inversely related to the diameter of the rod, and in the illustrated embodiment, is preferably approximately .073" for a No. 9 wire, approximately .069" for a No. 8 wire, and approximately .065" for a $\frac{3}{16}$ " wire. Thus, the spacing between successive grooves as illustrated herein is preferably less than .08" for the illustrative range of rod diameters.

The improved groove design disclosed herein provides the highly desirable features set forth above in a novel and simple manner. The grooves may be formed simply and expeditiously by knurling, the groove design permitting the knurling operation with effectively optimum minimum power requirements while providing the highly desirable positive rod retention features discussed above.

While I have shown and described certain embodiments of my invention, it is to be understood that it is capable of many modifications. Changes, therefore, in the construction and arrangement may be made without departing from the spirit and scope of the invention as defined in the appended claims.

I claim:

1. In a reinforcement for masonry wall construction having a pair of cylindrical, metal, parallel, spaced side rods and a plurality of cross rods extending between said side rods, means for providing effectively positive retention of said side rods against longitudinal movement through a body of surrounding mortar, said retention means comprising means in said side rods defining a pair of diametrically opposite series of axially aligned spaced grooves, said grooves being spaced apart a fraction of an inch, each groove opening radially outwardly and being defined by a radially inner substantially planar rectangular bottom surface extending right angularly chordally to the axis of the side rod and having

an axial width of approximately .024 inch, a chordal length of at least approximately one-half the diameter of said side rods, and a pair of opposed, substantially planar side wall surfaces extending angularly outwardly from the axially opposite ends of said bottom surface, said side wall surfaces being oppositely inclined at an angle of approximately 135 degrees to said bottom surface, the maximum depth of said grooves being at least approximately .014 inch, said side rods further including an upset portion at the radially outer edge of at least one of said side wall surfaces and defining a surface substantially coplanar with the side wall surface.

2. The reinforcement of claim 1 wherein the depth of the grooves in said side rods having a first diameter being at least as large as the depth of the grooves in different side rods having a second, smaller diameter.
